(57) **CLAIM**

The ornamental design for a storage rack as shown and
described.

DESCRIPTION

FIG. 1 depicts a front elevation view of a storage rack
showing our new design according to a first embodiment.

FIG. 2 depicts a left side elevation view thereof.

FIG. 3 depicts a right side elevation thereof.

FIG. 4 depicts a bottom plan view thereof.

FIG. 5 depicts a top plan view thereof.

FIG. 6 depicts rear elevation view thereof.

FIG. 7 depicts a front, upper, right perspective view thereof.

FIG. 8 depicts a front, lower, right perspective view thereof.

FIG. 9 depicts a front elevation view of a storage rack
showing our new design according to a second embodiment.

FIG. 10 depicts a left side elevation view thereof.

FIG. 11 depicts a right side elevation thereof.

FIG. 12 depicts a bottom plan view thereof.

FIG. 13 depicts a top plan view thereof.

FIG. 14 depicts rear elevation view thereof.

FIG. 15 depicts a front, upper, right perspective view
thereof; and,

FIG. 16 depicts a front, lower, right perspective view
thereof.

The dash lines represent portions of the article forming no
part of the claimed design. The dot-dash lines represent
boundaries of the claimed design.

1 Claim, 6 Drawing Sheets
